UNITED STATES PATENT OFFICE.

GEORGE R. CORNWALL, OF RYE, NEW YORK.

EXPOSING-TABLE.

1,171,772.

Specification of Letters Patent. Patented Feb. 15, 1916.

Application filed August 26, 1910. Serial No. 579,069.

To all whom it may concern:

Be it known that I, GEORGE R. CORNWALL, a citizen of the United States, and a resident of Rye, in the county of Westchester 5 and State of New York, have invented new and useful Improvements in Exposing-Tables, of which the following is a specification.

The invention relates to exposing tables 10 for exposing sensitized surfaces to the action of light through a design carrying medium and to the apparatus associated therewith.

Objects of the invention are to provide 15 novel mechanisms for rapid and easy handling of printing plates and other surfaces, and especially those of large size; to provide novel means for rendering the frame readily and easily accessible to an operative 20 while it is securely held upon its mounting; to provide novel mechanism for readily moving the exposing frame around within the shop and also outside to be exposed in the exterior light when desired; to provide 25 a novel track for running the exposing frame on to the floor and also out of the window; to provide novel means for rendering the exposing frame accessible from the floor while carried on an elevated track. 30 These and other objects of invention will in part be obvious and will in part more fully appear herein.

The invention consists in the novel parts, constructions, arrangements, combinations 35 and improvements herein shown and described.

The accompanying drawings, referred to herein and forming a part hereof, illustrate one embodiment of the invention, the same 40 serving in connection with the description herein to explain the principles of the invention.

Of the drawings: Figure 1 is an elevation 45 showing the window of a building in section, and showing in elevation the track in position to run the frame in and out, and also showing in dotted line the track in depressed position; Fig. 2 is a plan corresponding to Fig. 1; Fig. 3 is an elevation 50 showing the frame track in cross section, the exposing frame and its mounting in elevation, and showing the exposing frame itself in two positions; Fig. 4 is an elevation looking at Fig. 3 from the left; Fig. 5 is a view corresponding to Fig. 3, showing the 55 exposing frame let down into horizontal

position but with its supports running in the track; Fig. 6 is a sectional plan on the line A—B of Fig. 4 looking in the direction of the arrows; and Fig. 7 is a fragmentary detail in elevation, with parts in section and parts broken away, of the mounting and control for the exposing frame.

Referring to the accompanying drawings, illustrating by way of example one embodiment of the invention, novel means are shown in connection with a window in the wall of a building for running a printing or exposing frame outside into the direct light and back into the building for insertion and removal of the work in connection with means for rendering the frame handy and accessible for inserting and removing and otherwise operating upon the work.

In the present embodiment a section 1 of 75 track is shown projecting horizontally from the bottom of the window opening 2, in the wall 3. Said track is shown supported externally of the building by means of inclined bracket arms 4 fastened beneath the 80 tracks and against the side wall of the building. Means are also provided to counteract any pivoting movement of the track about the point where it is supported by the brackets 4 and also to prevent any outward pull or rotation about the point of support of the arms 4 on the building wall or the point of support for the track at the bottom of the window opening 2. For this purpose each of the rails 5 and 6 has at its 90 inner end, near the inner face of the building wall 3, plates 7 and 8, attached to the said track rails 5 and 6, respectively, in a suitable manner, as for instance, by being riveted thereto. Each of the plates 7 and 8 95 has a downwardly projecting arm or lug 9 fixed thereto, shown as a plate bearing on and also preferably fastened against the inner face of the building wall. The track may also be fastened directly to a window 100 sill 10.

According to certain features of the invention a sectional track is provided internally of the building movable into a position on the floor of the building and from such position into alinement with the exterior section 1 of the track, for the purpose in such first named position of running the frame to different points within the building for inserting, removing or otherwise operating upon the work, or making interior exposures with artificial light and in the 110

other position of running the frame out of the window when exposures are to be made outside.

The interior section of track 20 comprises the rails 21 and 22. These rails are movable from the floor into alignment with the exterior track as described and for this purpose are shown pivoted respectively to a pair of arms 23 and 24 near one end thereof, the arm 23 being also pivoted to a support 25 and the arm 24 to a support 26 on the floor of the room, or some other suitable support. A corresponding pair of arms 27 and 28 are pivotally connected to the two rails 21 and 22, respectively, near their other ends. The arms 27 and 28 are likewise pivotally carried, respectively, upon the supports 29 and 30 fixed to the floor. Between the rails 21 and 22 are provided suitable stiffening devices, shown herein, as bars 31 and 32. Each of said bars extends diagonally across from one of the tracks 21 and 22 to the other, one end of each of said bars being fixed to one of the track rails 21 and 22, and the other end of each bar being connected to the other rail, the two bars are also arranged transversely of each other, and are fastened together at their crossing point by a suitable rivet or bolt 33, or otherwise.

Suitable means are provided for guiding the movable section 20 of the track into alignment with the fixed section 1. For this purpose the plates 7 and 8 project, at the sides, beyond the ends of the tracks 5 and 6, the first part of said projecting portions being straight and the outer part of each being flared or as shown at 40 and 41, and a similar straight and flared construction is provided also upon the bottom as shown at 42. The track rails are channeled with their open or channeled parts facing each other, the top, side and bottom of each rail co-operating with the car for the exposing frame as more fully described hereinafter. Upon the tops and near the ends, of the rails 21 and 22, respectively, are shown pins 44 and 45. Hooks 46 and 47 are correspondingly pivoted upon the tops, and near the ends, of the rails 5 and 6, respectively. When the section 20 of the track is swung upwardly into the position shown in full lines in Fig. 1 from the position shown in dotted lines therein, the left-hand ends of the rails 21 and 22 will be sure to pass within the flared edges of the plates 7 and 8, as they pass inwardly, the straight portions of said plates which are adjacent to but projecting beyond the corresponding ends of the rails 5 and 6 will bring the ends of the connecting rails into exact alignment and the hooks 46 and 47 will then hook the pins 44 and 45 to firmly hold the tracks together in alignment. The channeled form of the rails 5 and 6 and 21 and 22 with the openings in the rails of each pair facing each other, and the top

sides and bottom of the rails co-operating with the car or mounting for the exposing frame, firmly holds the car in position against variations in position of the frame above its support, and against the wind pressure or movement of the frame upon its mounting, and serves to keep it on the track securely at all times, as well as having other advantages. The rails 21 and 22 are flared or bent downwardly on the lower side, as shown at 48 in Fig. 1 and outwardly at the sides as shown at 49 and 50 in Fig. 2 to permit the car to be conveniently run off onto the floor and back into the track.

Means for elevating and lowering the tracks are provided, and the form thereof herein illustrated comprises a winch 60 mounted in a frame 61 and provided with a gear 62 with which meshes a pinion 63 on the shaft 64. The shaft 64 may be turned in a suitable manner, as by a crank 65. A rope or chain 66 is wound about the winch 60 and passes through a single block 67. Attached to the rope 66 are two branches 68 and 69 terminating respectively in hooks 70 and 71. On the outside of the rail 21 is a link or ear 72 and a similar link or ear 73 is provided on the outside of the rail 22.

The exposing frame may be on the section 20 of the track in the lowered or floor position and the hooks 70 and 71 are hooked into the ears 72 and 73. The crank 65 is then turned to raise the section 20 of the track into alignment with the exterior section 1, that is, to the full line position shown in Fig. 1 and after the two sections of track are aligned and hooked together by the hooks 46 and 47, the hooks 70 and 71 may be unhooked and run up out of the way, and the exposing frame may be run out upon section 1 of the track. After the exposure is completed, the exposing frame may be run back, the hooks 70 and 71 may be re-hooked into the ears 72 and 73, and the crank 65 again used to lower the section 20 of the track to the dotted line position shown in Fig. 1.

Means of suitable or convenient form are provided for rotating the exposing frame into a vertical or horizontal, or intermediate position, as may be desired, and as shown in Fig. 3. As shown herein the exposing frame 80 is provided with trunnions 81 and 82 journaled in the standards 83 and 84. The trunnion 82 is not journaled directly upon the standard 84, but is shown of beveled or conoidal form fitting into and enclosed within a corresponding piece 85 supported directly in the standard 84, and held in position by the clamping screw 86. Fitted within the trunnion 82 is a screw bolt 87, projecting through the center of the shaft of the member 85 outwardly. Threaded on the projecting end of the screw bolt 87 is a nut 88 to which is pivoted a handle 89. By turning the nut 88 on the screw bolt

87, the trunnion 82 may be left free to rotate in the cap 85 or be clutched or clamped tightly thereto, in order to leave the frame free to be swung, or to be clamped tightly 5 after it has been swung to the desired position.

Novel means are provided by the invention for lowering and raising the exposing frame and for moving it to one side or the 10 other relatively to its support to present it in the most advantageous position for handling the work and for giving the frame a horizontal rotative movement with reference to its lower support or base. In the embodied form of such means, the standards 15 83 and 84 are shown of triangular form, the standard 83 comprising two legs 189 and 90 connected at the top and extending downwardly and diverging from each other, and 20 the standard 84 having two similar legs 91 and 92. At their bottom end the said legs 189 and 90 are connected by a cross web 93 and the legs 91 and 92 by a cross web 94. Said standards are carried upon a table 110 25 which is rotatably mounted upon the car which is adapted to run on the tracks. At their bases the standards 83 and 84 are pivotally mounted upon a rod 95, which rod passes through apertured lugs 96 and 97 in 30 said standards, respectively. At the other ends of their bases, said standards 83 and 84 rest upon and embrace a rod 98 by means of the recessed lugs 99. Each of said rods 95 and 98 is carried by the table 110. Said table 110 comprises four arms 111, 112, 115 35 and 116. The rod 95 is supported in the apertured ends of said arms 111 and 112 of the said table 110, said shaft being held from lateral displacement in its bearings on 40 said arms by collars 113 and 114. The rod 98 is carried in the apertured end of the arms 115 and 116 of the table 110 and is held from longitudinal displacement in its bearings on said arms by the collars 117 and 45 118. The table 110 is rotatably supported upon the car 120 by a central bearing through which passes the king pin 121, said pin 121 being fast to table 110 and projecting down through an aperture in the car 120. 50 A pin 123 serves to fasten the pin 121 in place below the car 120. In each of the arms of the table 110 is pivoted a roller 125, which is set radially with respect to the center of rotation of the table 110. These rollers run upon a circular track 130, which is 55 a part of the car 120.

The car 120 is shown having four arms 131, 132, 133 and 134 extending outwardly from its center where the table 110 is 60 pivoted, and the track 130 is integral with, or fixed to, said arms. A connecting cross web 135 connects the outer ends of the arms 131 and 132. A similar cross web 136 connects the outer end of the arms 133 and 134. 65 In the outer end of the arm 131 is mounted

a roller 140 and in the outer end of the arm 133 a roller 141. These two rollers are at one side of the frame and when the car is on the track they run in the same channeled rail. When running on the track the rollers 70 bear upon the bottom web of the channel while the end and top of the car 120, at the rollers, is shaped to fit within the side and top web of the channel with easy play, (see Fig. 3). A similar roller 142 is shown 75 pivoted in the end of the arm 132 and a roller 143 in the end of the arm 134. These are similarly constructed and arranged and are shown running on the bottom web of the channel 22, the side and top ends of the car 80 100 at this point fitting within the side and top webs of the channel in the same manner, (see Fig. 3).

Means for fastening the car and table together against rotation are provided, and 85 the embodied form thereof comprises a clamping screw 151 having a turning head 150. Said screw is mounted in the cross web 135 of the car 120 and extending inwardly is threaded into the central boss of the car 90 120 and by rotation may be thrust against, and retracted from, the pivot pin 121 to firmly clamp or to release the table 110 against rotation on the car 120.

Means are provided for rocking the standards 83 and 84 about the rod 85 to bring the exposing frame down into position where it will be at a convenient height for a workman standing on the floor and so as to be free and accessible on at least three sides 100 thereof. For this purpose a rack bar 160 is shown pivoted on the rod 98, and a pinion 161 is carried on a stub shaft 162 journaled in the cross web 94 at its junction with the leg 92 of the standard 84. The stub shaft 105 162 is shown with a squared end 163, to take a crank 164. Pivoted on either side of the pinion 162 are shown the pieces 165 and 166, which pass on either side of the rack bar 160. Journaled in the ends of these 110 pieces are rollers 167 and 168, which run on the back face of the rack bar and keeps it in mesh with the pinion 161.

The manner of operation of the mechanism just described is substantially as follows: The manner of swinging the exposing table 80 on its pivots has always been described. The exposing table and its standards may be rotated about the pin 121, the supporting rollers for the table 110 running around on their track 130. When in the proper position the head 150 of screw 151 is turned to clamp the parts in the adjusted position. When it is desired to lower the table, the crank 164 is fitted to the head 125 163, the parts being then in the position shown in Fig. 3, and the exposing table being swung from the dotted to the full line position in said figure, or vice versa. The pinion 161 will thus travel along the rack 130

bar 160 and the exposing table 80 will be let down to the position shown in Fig. 5. In this position it is horizontal at a convenient height from the floor and freely accessible on three sides. The interlocking construction of the tracks and the car 120 will prevent any tipping of the structure by reason of the table swinging out to one side. It will be understood that the table may be used without the raising and lowering tracks, and in Figs. 3 and 5 of the drawings, fixed supports 170 and 171 for the tracks 21 and 22 are shown.

The exposing table mounted on its car can be used for inside work entirely, the exposure being made by artificial light, or it can be used with the track, or with either as desired. Such a frame may be used with either a movable or a fixed track, as the frame may be let down while supported on the elevated track so as to be of the right height and easily accessible around the sides, and it can be swung around so as to be let down on any side desired.

Other objects and advantages will be obvious to those skilled in the art or may be ascertained by practical use of the invention.

The invention, in its broader aspects, is not limited to the particular construction shown, nor to any particular constructions by which it has been or may be carried into effect, as many changes may be made in the construction without departing from the main principles of the invention and without sacrificing its chief advantages.

What I do claim as my invention and desire to secure by Letters Patent, is:—

1. An exposing table apparatus including in combination an exposing frame, standards upon which said frame is mounted to swing about a substantially horizontal axis, a table upon which said standards are mounted, said table being rotatable about a substantially vertical axis, and means for swinging said standards to lower said exposing table at one side of its base.

2. An exposing table apparatus including in combination an exposing frame, standards upon which said frame is mounted to swing about a substantially horizontal axis, a table upon which said standards are mounted, said table being rotatable about a substantially vertical axis, and means for swinging said standards about a substantially horizontal axis whereby said exposing table may be lowered at one side of its base.

3. An exposing table apparatus including in combination an exposing frame, standards upon which said frame is mounted to swing about a substantially horizontal axis, a table upon which said standards are mounted to rotate about a substantially horizontal axis, means for varying the position of said exposing frame relative to said standards without moving said standards,

and supporting means upon which said table is rotatable about a substantially vertical axis.

4. An exposing table apparatus including in combination an exposing frame, standards upon which said frame is mounted to swing about a substantially horizontal axis, a table upon which said standards are mounted to rotate about a substantially horizontal axis, and connections between said standards and said table for rocking said standards about said horizontal axis while holding them against the action of gravity.

5. An exposing table apparatus including in combination an exposing frame, standards upon which said frame is mounted to swing about a substantially horizontal axis, a table upon which said standards are mounted to rotate about a substantially horizontal axis, and a rack and pinion connection between said standards and said table, the rack being mounted on one and the pinion on the other.

6. An exposing table apparatus including in combination an exposing frame, standards upon which said frame is mounted to swing about a substantially horizontal axis, a table upon which said standards are mounted to rotate about a substantially horizontal axis, connections between said table and standards comprising a rack pivotally mounted upon one and a pinion rotatably mounted on the other and meshing with said rack.

7. An exposing table apparatus including in combination an exposing frame, standards upon which said frame is mounted to swing about a substantially horizontal axis, a table upon which said standards are mounted to rotate about a substantially horizontal axis, supporting means upon which said table is rotatable about a substantially vertical axis, wheels upon which said supporting means are mounted, a track along which said wheels travel and means for holding said supporting means to the track when the standards and exposing table are rocked to one side.

8. An exposing table including in combination a car provided with wheels, a table fixed to said car to rotate relatively thereto about a vertical axis, means for locking said car and table together, standards mounted upon said table, a horizontal shaft carried by said table and upon which said standards are mounted to swing, an exposing table mounted upon said standards to swing about a horizontal axis, and means for so swinging said standards.

9. An exposing table including in combination a car provided with wheels, a table fixed to said car to rotate relatively thereto about a vertical axis, standards mounted upon said table, a horizontal shaft carried by said table and upon which said stand-

ards are mounted to swing, an exposing frame mounted upon said standards to swing about a horizontal axis, means for locking said standards and frame together, 5 and means for so swinging said standards.

10. An exposing table including in combination a car provided with wheels, a table fixed to said car to rotate relatively thereto about a vertical axis, standards mounted 10 upon said table, a horizontal shaft carried by said table and upon which said standards are mounted to swing, an exposing frame mounted upon said standards to swing about a horizontal axis, a rack bar 15 and a gear meshing therewith, said rack bar and gear being carried the one by said table and the other by one of said standards.

11. An exposing table including in combination a car provided with wheels, a table 20 fixed to said car to rotate relatively thereto about a vertical axis, means for locking said car and table together, standards mounted upon said table, a horizontal shaft carried by said table and upon which said standards are mounted to swing, an exposing 25 frame mounted upon said standards to swing about a horizontal axis, means for so swinging said standards, a rack bar and a gear meshing therewith, said rack bar 30 and gear being carried the one by said table and the other by one of said standards.

12. An exposing table including in combination a car provided with wheels, a table fixed to said car to rotate relatively thereto 35 about a vertical axis, means for locking said car and table together, standards mounted upon said table, a horizontal shaft carried by said table and upon which said standards are mounted to swing, an exposing 40 frame mounted upon said standards to swing about a horizontal axis, means for so swinging said standards, means for locking said standards and frame together, a rack bar and a gear meshing therewith, 45 said rack bar and gear being carried the one by said table and the other by one of said standards.

13. An exposing table including in combination a car provided with wheels, a circular track formed upon said car, a table 50 pivoted centrally upon said car and having rollers running on said track, a horizontal

shaft carried by said table, standards spaced apart and hinged upon said horizontal shaft, a rack bar and a gear meshing therewith, 55 one carried upon one of said standards at the opposite side from said shaft and the other upon said table, and a frame mounted between said standards to swing horizontally. 60

14. An exposing table including in combination a car provided with wheels, a circular track formed upon said car, a table pivoted centrally upon said car and having rollers running on said track, means for 65 fastening the table and car together, a horizontal shaft carried by said table, standards spaced apart and hinged upon said horizontal shaft, a rack bar and a gear meshing therewith, one carried upon one 70 of said standards at the opposite side from said shaft, and the other upon said table, and a frame mounted between said standards to swing horizontally.

15. An exposing table including in combination an elevated track, a support mounted upon said track, an exposing frame, standards upon which said exposing frame is pivotally mounted, said standards being mounted upon said support to swing between a position above said support and a position beside said support carrying with them said exposing frame, said track and support being constructed to preserve said support upright when said standards and 85 frame are in either position. 75

16. The combination with a track extending horizontally from a window opening outwardly, and a track within the building adapted to rest upon the floor of the building, means for elevating said inner track into alignment with said outer track and for lowering it to the floor of the building and a car adapted to run on said tracks and on the floor and an exposing frame 95 movably mounted on said car, to be rotated in a plurality of directions. 90

In testimony whereof, I have signed my name to this specification, in the presence of two subscribing witnesses.

GEORGE R. CORNWALL.
